ADJUSTABLE OIL JUG STAND

Fiore Massucci, Waterbury, Conn.

Application September 8, 1947, Serial No. 772,613

4 Claims. (Cl. 254—95)

1

This invention relates to stands, and more particularly to an adjustable stand for supporting a jug in such a manner as to avoid wasting of the oil or other liquid while the jug is being filled therewith.

When oil jugs are filled in the usual manner, the oil is frequently spilled upon the ground or the floor. This soon creates an undesirable condition, particularly when the oil is drawn from a stationary source such as a drum upon a rack, because the vicinity of the drum usually becomes saturated with the oil to a point where only the most thorough and frequent cleaning will remove the oil. The spilled oil not only attracts dirt, but is malodorous, and is a serious fire hazard. Further, the spilled oil cannot be reclaimed, and is an item of expense.

One cause of oil spillage is the difficulty of locating the mouth of the jug accurately to receive the stream of oil. When the oil is drawn from a faucet, the faucet is usually located at a considerable height above the ground or other support in order to permit jugs of large size to be positioned thereunder. Thus, the person filling the jug must either guess at the proper position of the jug to prevent spillage, or must tediously hold the mouth of the jug to the faucet.

Another cause of spillage is the foaming property of the oil whereby the falling stream of oil will entrain air at such a high rate that the foam will fill the jug while the oil occupies only a fraction of the capacity of the jug. When this occurs, the only practicable way to secure a full measure is to continue drawing oil into the jug, permitting the displaced foam to run over the top and down the outside of the jug.

Accordingly, one object of this invention is to provide an oil jug stand having a platform which is vertically adjustable in order to support jugs of varying sizes in close proximity to a faucet.

Another object is to provide a device of the above nature which includes reversible mechanism for raising and supporting the oil jug in such a position that the mouth of the jug receives the outlet end of the faucet therein, whereby the jug will be accurately located to receive the oil.

Another object is to provide a device of the above nature which includes a removable oil receptacle for receiving the foam displaced from the jug, whereby the oil content of the foam will be saved.

A further object is to provide a device of the above nature which will be simple in construction, inexpensive to manufacture, easy to install and manipulate, compact, ornamental in appearance, and very efficient and durable in use.

With these and other objects in view, there have been illustrated on the accompanying drawing two forms in which the invention may conveniently be embodied in practice.

In the drawings,

2

Fig. 1 shows a side elevation of the improved adjustable oil jug stand and a jug thereon, as associated with the faucet of a supply drum supported upon a rack.

Fig. 2 is a cross sectional view of the stand showing one form of retaining element.

Fig. 3 is a fragmentary cross-section, taken on the line 3—3 of Fig. 2.

Fig. 4 is a fragmentary cross-section, taken on the line 4—4 of Fig. 2.

Fig. 5 is a perspective view of a modified form of retaining element.

Referring now to the drawings in which like reference numerals denote corresponding parts throughout the several views, the letter J indicates an oil jug supported in engagement with a faucet F of an oil drum D upon a rack R by the improved oil jug stand indicated generally as 10.

The stand 10 includes a hollow rectangular body 11, preferably of metal, having an outwardly flared base 12. The body 11 supports a transverse tubular bearing 13 centrally therein by means of an interior cylindrical flange 14 upon one wall thereof and an aperture 15 in the opposite wall. The tubular bearing 13 includes an end flange 16 secured against the outer face of the body 11 by screws 17.

A shaft 18 is carried by the bearing 13, and includes a central gear portion 19, an end gear portion 20, and an end portion 20a projecting outwardly of the body 11. A rack 21 is vertically supported in mesh with the central gear portion 19 by a vertical guideway 22 in tangent relation to the bearing 13 and formed in a lateral projection 23 thereof. A horizontal perforated platform 24 is secured to the upper end of the rack 21.

Adjacent to the aperture 15 of the body 11, said body includes a radial guide 25 slidably holding a retaining element in the form of a dog 26 which extends through an aperture 27 in the bearing 13 for engagement with the end gear portion 20 of the shaft 18.

The dog 26 is urged downwardly by a coil spring 28 within the guide 25, said spring having a backing disk 28a retained by a vertically adjustable screw 29. The screw 29 is mounted in a threaded bushing 29a, mounted in the upper end of the guide 25.

In order to collect the oil which may be spilled, a frusto-conical deflector 30 forms a partition across the base 12, and is supported therein by means of a deflector flange 30a and rivets 31, said deflector being provided with a central drain opening 32 whereby the spilled oil will be guided into a pan 33, slidably mounted upon horizontal guides 34 in the base 12.

An aperture 35 is provided in the side of the base 12, whereby the pan 33 may be removed for emptying, said pan being provided with an exterior handle 36, an upturned spout 37, and an apron 38 to facilitate the pouring of oil from

the pan. The outwardly projecting end portion 20a of the shaft 18 is provided with a radially-extending handle in the form of a bar 39 having a threaded end 40 secured in said end portion 20a. In order to release the dog 26, said dog is provided with an angular upstanding release rod 41 extending outwardly of the body 11 through a slot 42. A knob 43 is provided on the end of the rod 41 to facilitate its operation.

Operation.

In use, the stand 10 will be placed below the outlet of a source of oil, such as the faucet F. The oil jug J will be placed upon the platform 24, and the handle 39 swung forwardly, whereby the platform 24 will raise the jug to a position in which the mouth of the jug will surround the oil outlet as shown in Fig. 1.

Various sizes of oil jugs may be accommodated, since the platform 24 may be raised to any extent necessary to bring the jug into proper relation with the oil outlet. When the handle 39 is released, the dog 26 will automatically prevent dropping of the platform with the jug thereon by virtue of its engagement with the teeth of the end gear portion 20. The oil will then be permitted to flow into the jug until the jug is full. Any foam which is formed during this operation may flow out of the top of the jug around the sides of the oil outlet, and down through the platform 24 and the deflector 38 into the oil pan 33.

When the jug is full, the upstanding release rod 41 may be lifted, whereupon the platform with the jug upon it will descend, and the jug may be removed from the platform. The pan 33 may be easily removed at intervals, and its contents discharged into the drum D or any other desired receptacle.

One advantage of this apparatus is that the oil jug may be positively located with reference to the oil outlet without undue effort on the part of the operator.

There will be no objection to the discharge of foam from the jug, as the oil which runs down the outside of the jug will be received in the pan 33, where it will be protected against contamination.

Another advantage of the oil jug stand, therefore, is that spilled oil will be efficiently conserved, thus avoiding the expense of wasted oil. It will be apparent that the stand will confine the spilled oil, thereby maintaining the premises in a clean condition, avoiding fire hazards, and minimizing objectionable odors.

Modified form

In Fig. 5 of the drawing, a modified retaining element is shown in the form of a lug 44, rectangular in cross section and having convergent lower surfaces 45 terminating in a rounded end 46.

The oil jug stand employing the lug 44 will be in all respects the same as the stand shown in Figs. 1, 2, 3, and 4, excepting that the lug 44 will be substituted for the dog 26, no release rod such as the rod 41, being required in this instance.

In the modified form of the invention the lug 44 will resiliently maintain the shaft 18 against rotation, and may be adjusted by means of the screw 29 and the spring 28 to exert sufficient force upon the gear portion 20 to support the desired weight upon the platform 24. When it is desired to lower the platform 24, it will merely be

necessary to swing the handle 39 rearwardly whereupon the spring 28 will yield sufficiently to allow the lug 44 to ride over the teeth of the gear portion 20.

While there has been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In an oil jug stand, a base, a hollow body thereon, a horizontal tubular bearing secured in and extending centrally across said body, said bearing including a vertical guide at a central point thereon, a rack slidable in said guide, a shaft rotatable in said bearing and including a central gear portion in engagement with said rack, a platform secured to said rack, means for rotating said shaft whereby the vertical position of said platform may be adjusted, and retaining mechanism for holding said platform in adjusted position.

2. The invention as defined in claim 1, in which said retaining mechanism includes an end gear portion on said shaft, a dog movably mounted on said body, a spring urging said dog into engagement with said gear portion, and a release means on said dog, whereby the dog may be released from said end gear portion.

3. The invention as defined in claim 1, in which said retaining mechanism includes an end gear portion on said shaft, a lug having a rounded end movably mounted in said body, and a spring urging said lug into engagement with said end gear portion, whereby said shaft and said platform will be resiliently held against movement.

4. The invention as defined in claim 1, in which said retaining mechanism includes an end gear portion on said shaft, a lug having a rounded end movably mounted in said body, a spring engaging said lug, and an adjustable screw pressing said spring to urge said rounded end into engagement with said end gear portion, whereby an adjustable force may be applied to said shaft to resist movement of said shaft and said platform.
